UNITED STATES PATENT OFFICE.

PHILEMON O. DICKINSON, OF NEWARK, NEW JERSEY.

DESIGN FOR A HANDLE FOR KNIVES, &c.

SPECIFICATION forming part of Design No. 25,636, dated June 16, 1896.

Application filed January 29, 1896. Serial No. 577,318. Term of patent 3½ years.

To all whom it may concern:

Be it known that I, PHILEMON O. DICKINSON, a citizen of the United States, residing in Newark, in the county of Essex and State of New Jersey, have invented and produced a new and useful Design for the Handles of Knives and Similar Articles, of which the following is a description, reference being had to the drawing accompanying and forming a part of the same.

The general outline of the handle is that of a terminal or gaine surmounted by double or repeated ovate.

In the drawing, A represents the shank, which is of the gaine form, and has its face decorated, as shown. Joining this shank is the diagonally-arranged ovate B, the breadth of which slightly exceeds the breadth of the upper part of the shank. This ovate bears on

its face the rococo design C, surrounding the disk D.

E is a second ovate, which is slightly larger than the first ovate B, is similarly diagonally arranged, and bears the rococo design F, surrounding the disk G.

H is a crest surmounting the upper ovate and of conventionalized shell design.

The essential features of design consist of the shank of gaine form, the two ovates, and the shell-like crest.

What is claimed as new is—

The design for handles for knives and similar articles, substantially as shown and set forth.

PHILEMON O. DICKINSON.
